UNITED STATES PATENT OFFICE

EDWARD E. PINKERTON, OF CHICAGO, ILLINOIS

PHONOGRAPH

Application filed November 5, 1923. Serial No. 672,702.

My invention relates to improvements in phonographs, and has for its object the provision of an improved construction of this character capable of reproducing records without material or confusing scratching sounds and generally improving the quality of the tone of the phonograph.

Other objects will appear hereinafter.

The invention consists in the combinations and arrangements of parts hereinafter described and claimed.

The invention will be best understood by reference to the accompanying drawings forming a part of this specification, and in which

Fig. 1 is a front view of a phonograph sound box embodying the invention;

Fig. 2, a partial section taken substantially on line 2—2 of Fig. 1;

Fig. 3, a partial section taken on line 3—3 of Fig. 1;

Fig. 4, a similar view to Fig. 1 but showing a modified form of construction;

Fig. 5, a sectional view of the construction shown in Fig. 4;

Fig. 6, a side view of the construction shown in Fig. 4;

Fig. 7, a sectional view taken on line 7—7 of Fig. 5;

Fig. 8, a side view of another modified form of construction;

Fig. 9, a section taken on line 9—9 of Fig. 8, and

Fig. 10, a sectional view of another modification.

The preferred form of construction as illustrated in the drawings comprises the usual sound box 10 mounted on the end of the usual tone arm 10' and equipped with the usual diaphragm 11. The sound box 10 also carries the usual needle arm 12 pivoted at 13 thereon and carrying at one end the usual needle 14 and secured at the other end to the diaphragm 11 at 15. So much of the construction is old and well known constituting the usual and common form of sound boxes for phonographs, the same constituting no part of my present invention except in so far as it co-operates with the construction and parts to be presently described.

A spring wire tension rod 16 is passed under the needle arm 12 and through perforated ears 17 secured to the rim of the sound box on opposite sides of the needle arm as shown. Adjusting nuts 18 are threaded on the ends 55 of the tension rod 16 and serve as means for adjusting the tension in said rod. The perforations in the ears 17 are somewhat higher than the under edge of the needle arm 12 so that tightening the nuts 18 introduces tension into both the needle arm 12 and the diaphragm 11 tending to bulge the diaphragm 11 outwardly as indicated by the dotted lines in Fig. 3. This tension in the diaphragm 11 and in the needle arm 12 takes up and prevents any lost motion in either or in the connection between them so that there can be no undue rattling or vibration of either and the only vibrations transmitted to the diaphragm are the vibrations caused 60 by the undulations or sound waves in the phonograph record. In this way scratching or other confusing and discordant vibrations are eliminated or lessened or softened and the quality and tone of the phonograph is 65 greatly improved.

In the construction illustrated in Figs. 4, 5, 6 and 7 two spring steel clips 19 are slidably engaged with the rim of the sound box 10 and the wooden tension rod 20 is passed under the needle arm 12 and through perforations in said clips so as to exert outward tension on the under side of said needle arm. The perforations 21 in the inner sides of the clips 19 are laterally elongated as shown in 70 Fig. 7 so as to permit of peripheral adjustment of the clips 19 as indicated by the dotted lines in Fig. 4. The inner edge 22 of the needle arm 12 is inclined as shown so that adjustment of the tension rod 20 toward or 75 away from the periphery of the sound box exerts greater or less outward tension on the needle arm and consequently greater or less outward tension on the diaphragm so that by simply sliding the clips 19 on the periphery of the sound box the tension in both the needle arm and diaphragm may be adjusted as 80 desired. The clips 19 are also provided with hooks or points 23 and by means of which a tension member in the form of a gut string 85 90 95 100

may be substituted for the wooden bar 20, the ends of the string being looped about or otherwise secured to the points 23.

In the form of construction illustrated in Figs. 8 and 9 a supporting lug or arm 24 is secured to the sound box 10 projecting parallel with the needle arm 12. A perforated band 25 is fitted over the ends of the needle arm 12 being held in place by the usual set 10 screw 25' which passes freely through a perforation provided in said band. The band 25 is provided with a threaded stem 26 passing through a perforation in the end of the lug 24 and an adjusting nut 27 is threaded on the 15 end of stem 26 and whereby the outward tension rod in the needle arm and diaphragm may be readily applied and adjusted as desired.

In Fig. 10 I have illustrated the construction disclosed in Figs. 5, 6 and 7 with a gut string 28 employed for producing the tension in the needle arm and diaphragm, said string being provided with knots 29 engaging the projections 23 on the clips 19. It 20 will be found that this arrangement constitutes a very simple and effective one for the purpose and one which imparts a very clear and mellow tone to the instrument.

The clips 19 are rotatably located on opposite sides of the periphery of the sound box so that portions of each clip are on the extremities of a diameter of said sound box. It will now be noted that when the clips are 25 revolved about the periphery of the sound box the tension element 20 will impinge against the converging under side of the needle arm 12 to an extent dictated by the amount of the rotation of the clips. It will be obvious that when the tension element is 30 in contact with that point of the under side of the needle arm which is nearest to the diaphragm 11, the stress on the needle arm along the diaphragm is at its greatest. It is 35 of course to be understood that both the clips are rotated to an equal degree and in 40 the same direction.

By careful rotation of the clips intermediate degrees of adjustment of the diaphragm, via the needle arm, can be obtained. 50 It will also be observed in the form illustrated in Fig. 5, 6, 7 and 10, that it will be possible to adjust the needle arm 12 by pushing the clips 19 away from the operator, in 55 the position shown in Fig. 10, thus bending the cat gut strip 28 about the downwardly projecting bend in the middle of the needle arm 12 as a fulcrum. Further slipping of the clips will cause a pressure on the needle arm 12 tending to raise the downwardly projecting bend which joins the diaphragm at 60 its center, and consequently to raise or bulge the diaphragm 17 itself in an upward or outward direction.

While I have illustrated and described the 65 preferred form of construction for carrying

my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:

1. The combination with a sound box of a phonograph having a diaphragm, of a needle arm pivotally mounted on said sound box and having a bend operatively connected with said diaphragm; clips slidably mounted on the rim of said box; and a tension member mounted on said clips and passing under and impinging against an inclined part of said needle arm whereby adjustment of said clips varies the tension on said needle arm, substantially as described.

2. The combination with a sound box of a phonograph having a diaphragm, of a needle arm pivotally mounted on said sound box and having a bend operatively connected with said diaphragm; clips slidably mounted on the rim of said box; and a flexible tension string secured to said clips and passing under and impinging against an inclined part of said needle arm whereby adjustment of said clips varies the tension of said needle arm, substantially as described.

3. The combination with a sound box of a phonograph having a diaphragm and a needle arm operatively connected therewith, of a flexible tension member traversing said sound box and passing under and impinging against an inclined part of said needle arm to exert outward tension thereon, substantially as described.

4. The combination with a sound box of a phonograph having a diaphragm and a needle arm operatively connected therewith, of perforated clips slidably engaging the rim of said sound box; and an elongated tension member passing under and impinging against an inclined part of said needle arm and through the perforations in said clips, the ends of said elongated tension member being secured to said clips, and said clips being slidably adjustable on the rim of said sound box to adjust said elongated tension member relatively to said needle arm, substantially as described.

In testimony whereof I have signed my name to this specification.

EDWARD E. PINKERTON.
